UNITED STATES PATENT OFFICE.

JAMES BOSSART, OF SAN FRANCISCO, CALIFORNIA.

MEMORANDUM-CALENDAR.

1,139,159.

Specification of Letters Patent.

Patented May 11, 1915.

Application filed July 17, 1914. Serial No. 851,618.

To all whom it may concern:

Be it known that I, JAMES BOSSART, a citizen of the United States, residing at San Francisco, in the county of San Francisco 5 and State of California, have invented new and useful Improvements in Memorandum-Calendars, of which the following is a specification.

This invention relates to calendars of that 10 type embodying a pad of leaves for presenting the calendar information and receiving memoranda, and the object of my invention is to provide a simple and convenient construction of index whereby any particular 15 leaf of the pad may be turned to for inspection in a ready and expeditious manner.

The invention consists of the features of construction, combination and arrangement of parts herein fully described and claimed, 20 reference being had to the accompanying drawing in which:—

Figure 1 is a perspective view of a calendar pad embodying my invention, showing the first leaf turned back. Fig. 2 is a plan 25 view of a portion thereof showing the index sheet.

Referring to the drawing, 1 designates a 30 memorandum pad comprising a backing 2, leaves 3 and binding or fastening members 4, the said leaves being perforated at their upper ends for the passage of said binding or fastening members, whereby the leaves are held in position, and whereby successive leaves may be turned backward to successively expose the same.

The leaves are arranged, in the usual 35 manner, in month groups, each group embodying a leaf for each day included therein, which groups are arranged in regular order, beginning with January at the top, and ending with December at the bottom.

In accordance with my invention, the leaves of the respective groups are provided 40 with marginal indicating tabs 5 for co-operation with an indicating table 6, which table is printed directly upon the marginal projecting portion of the backing 2 or upon a sheet secured thereto. The tabs of the leaves 45 of the month groups bear indicating characters peculiar to the groups, which may con-

sist of the first letter of the name of the month of each group—J, F, M, etc., and the tabs of each group are arranged in predetermined relationship to the indications upon the table 6.

As shown, the indications upon the table 6 consist of the month numerals from 1 to 31, inclusive. These month numerals, for convenience, extend around the side and bottom margins of the backing 2 so as to be clearly exposed to view, and the tabs upon the leaves of each group representing corresponding days of the month period represented by that group are arranged to register with the associated or corresponding month numerals in the table 6. Thus, for instance, the tab F, attached to the leaf of the Feb. group representing the 18th day of that month, is arranged in registry with the numeral 18 of the table 6.

From the foregoing, it will be readily understood that the invention provides an index by means of which a leaf appropriate to any particular day of any particular month may be easily, quickly and conveniently found for inspection by simply locating the particular tab of the month group which registers with the day numeral in the day table, whereupon the particular leaf in question may be exposed to view, allowing notes or memoranda of any kind made at any time to be easily reached and inspected, or a leaf appropriate to any future date to be reached for the inscription of notes or memoranda thereon.

I claim:—

A calendar comprising a base, fastening members projecting upwardly therefrom, and a pad of leaves mounted upon the base and engaging said fastening members so as to be individually turned back for reference thereto, said leaves being of smaller dimensions than the base so as to dispose portions of the latter to provide marginal extensions on at least three sides thereof, said extensions being provided with substantially equal divisions of a month index table bearing the month day numerals in regular order, the said leaves being arranged in superposed month groups and the leaves of the re-

spective groups being provided at their sides with index tabs bearing thereon indications of the months to which the groups are appropriated, said tabs being arranged in registration with the corresponding month day numerals upon the said marginal extensions of the base.

In testimony whereof I affix my signature in presence of two witnesses.

JAMES BOSSART.
